SNOWSHOE BINDING

Harold Howe, Rowayton, Conn., assignor to Howe Folding Furniture, Inc., New York, N. Y., a corporation of New York

Application December 24, 1956, Serial No. 630,174

4 Claims. (Cl. 36—4.5)

This application relates to a snowshoe binding characterized by providing control of the snowshoe primarily from the heel of the user's boot.

An object of the invention is to provide a simple and efficient snowshoe binding.

Another object of the invention is to provide such a binding in which the parts coact to provide control from the heel of the user's boot.

Another object of the invention is to provide a binding which may be readily assembled on a snowshoe and which serves to hold both the toe and the heel of a user's boot from displacement laterally of the snowshoe while permitting the heel to rise freely from the snowshoe. The invention will best be understood if the following description is read in connection with the drawings, in which:

Figure 1 is a plan view of the snowshoe binding.

Figure 2 is a perspective view showing one embodiment of the binding positioning a user's boot on a snowshoe.

Figure 3 is a bottom plan view showing the relation of the parts of the binding to the sole of the boot with part of the webbing omitted.

Figure 4 is a vertical sectional detail view taken on the line 4—4 of Figure 1.

Figure 5 is a plan view showing a modified form of triangular heel support means.

Figure 6 is a detail view through the frame of the snowshoe showing hook means for adjusting of one end of heel support means, and

Figure 7 is a top plan view of another modification of the invention showing control straps extending from the snowshoe frame adjacent the toe cord to adjacent the respective ends of the heel piece or to the instep strap.

In the embodiment of the invention disclosed herein the binding comprises a toe piece assembly and a combination instep and heel engaging piece, the latter carrying means serving both to maintain the boot properly within and against the toe piece and at the same time preventing swinging of the heel of the boot from side to side relative to the snowshoe.

The toe piece comprises a strap 10 which extends over the toe of the boot 12 and is engaged with the snowshoe on either side of the boot close to the boot in any suitable way. As shown herein the strap 10 is passed under the toe cord 14 which comprises part of the snowshoe lacing, on either side of the boot, and the ends of the strap are then secured together over the toe of the boot.

The toe cord is a cross lacing of enlarged size and strength at the rear margin of the spaces conventionally provided in the lacing so that the toe of the user's boot may move down into it as the heel of the foot is raised with each step.

If desired a toe cover member 16 may be also provided, of substantially greater width than the width of the toe strap 10, through which the toe strap may be passed to hold member 16 in position over the toe of the boot thus giving wider frictional contact and promoting comfort by

2

distributing the pressure of the strap. As shown strap 10 is passed through the opposed pairs of slots 17a and 17b in member 16 both before and after being passed under the toe cord on either side of the boot, thus engaging member 16 and making two passes over it.

The toe piece is distinguished from other toe pieces of which I have knowledge by what I will designate as a stop member 18 extending at right angles to the toe strap 10 and suitably secured at one end, 18a, to the snowshoe preferably to the toe cord 14, as for example by raw hide lacing 15, and suitably secured at its other end, 18b, to the toe strap assembly, and preferably to toe cover member 16 if it is employed as part of the toe piece assembly, as by lacing 19. At one end of member 18 a plurality of sets of lacing holes have been provided so that the length of member 18 may be adjusted according to the length of the user's boot.

Member 18 is desirably an inch and one-half or more in width to provide contact with the front end of the boot over and around the toe of the boot and thus coacts with the toe strap 10 in providing means for positioning the toe of the boot and fixing the position of the boot forwardly of the snowshoe.

Extending under and around the boot at the instep is the instep strap 20 which also may have threaded thereon a cover member 22. Like the toe strap the instep strap is of course adjustable for accommodation to boots of different sizes and for this purpose these straps may be punched with holes different distances from one end of the strap and provided with a buckle at the other end of the strap in well known manner.

The instep strap 20 is threaded through slits 23 provided adjacent the forward ends of a U-shaped heel piece 24 which extends around the heel of the boot and is held in close frictional engagement with the heel by its engagement with said instep strap 20 on either side of the boot. Desirably a plurality of pairs of slits 23 are provided in the respective ends of member 24 so that a given member 24 may be used with boots of different size, the pair of slits 23 selected for engagement with the instep strap 20 being the pair which will best serve the purpose of holding the member 24 tightly around the heel of the boot. It is desirable that the member 24 be of substantial height to provide a substantial area of frictional contact with the boot heel and I have obtained good results with such members having a height of from 1½" to 2" and thus able to frictionally engage the heel of the boot from adjacent the bottom of the heel up to a point on a level with the vamp of the boot.

An important part of my invention is the provision of means such as strap 26 for engaging the heel piece 24 at or adjacent the rear of the heel, said member having forwardly extending portions adapted for connection to the snowshoe on opposite sides of the user's boot but spaced laterally from the boot to provide a triangularly disposed support for the heel exerting pressure on the heel from points spaced apart a substantial distance, preferably the full width of the snowshoe.

While the connection between members 26 and 24 may be detachable I prefer to provide rigid engagement as for example by rivets 28 as shown herein.

Member 26 may comprise two separate straps each attached at one end to heel piece 24 behind the heel and extending forwardly and attached at the other end to the snowshoe at or adjacent to the respective side portions of the snowshoe frame F, at points spaced apart substantially the full width of the snowshoe, or preferably may be a single strap secured intermediate its ends to the heel piece 24 with its ends extending forwardly and secured to the snowshoe at points well spaced apart on opposite sides of boot 12, preferably adjacent the ends of the toe strap

but rearwardly of it. This triangular support for the heel is provided, which serves both to determine the position of the boot rearwardly of the snowshoe, and, because of the wide spacing between the ends of member 26, prevents the heel from moving substantially from side to side relative to the snowshoe.

The construction shown herein provides a toe piece assembly which coacts with the heel control means to position the boot on the snowshoe and provide firm control of the snowshoe primarily from the heel, making it much easier and less tiring for the user to manipulate the snowshoe than if the control is primarily from the toe with straps to the heel that are not spaced away from the sides of the boot. Such heel strap means fail to fix the position of the heel and permit it to move from side to side on the snowshoe.

It will be seen that the instep strap 20 coacts with the U-shaped heel piece 24 providing instep support and at the same time holding member 24 in close frictional engagement around the back and sides of the heel portion of the boot, and that the member 24 coacts with means 26 to hold the latter in position at the back of the heel of the boot. The length of the respective free ends of means 26 may be adjusted according to the size of the boot and also to fix the boot in angular relation to the snowshoe if such position is desired by the user.

To facilitate the attachment of the ends of heel control means 26 at or adjacent the respective sides of the snowshoe, the means 26 may comprise three strap portions 26a, 26b and 26c, members 26b and 26c each having a slit 30 adjacent one end so that this end of the strap may be looped around the side frame of the snowshoe or if desired around one or more of the cross lacings of the snowshoe adjacent the side frame, the other ends of said members 26b and 26c having a buckle to adjustably engage the respective ends of member 26a which in this case is provided with a series of holes adjacent each of its ends for engagement with the buckles carried by members 26b and 26c.

While the parts comprising this binding may all be made of soft flexible leather or rawhide it will be understood that the invention is not limited to the use of any particular materials. It will be understood for example, that the heel piece may comprise a metal strap with provision for adjusting its length by providing it with one or more coil spring sections. The important thing is to provide heel support means which is triangular in form i. e. extending to the rear of the heel from points located forwardly of the heel and spaced well apart from the respective sides of the boot.

As shown in Figure 5, a flat flexible steel band member 32 is riveted to a U-shaped heel piece 24, made of leather or other suitable material able to frictionally engage the heel of the boot, and the steel straps 34 and 36 may be welded to opposite ends of member 32 to extend on opposite sides of the boot to points on the snowshoe spaced laterally from the boot, each of said steel straps 34 and 36 including a coil spring section 38 to make these strap members self-accommodating to different sizes of boots. The outer ends of the steel straps 34 and 36 may be fastened to the snowshoe in various ways as for example by attachment to hooks 40 anchored in the respective sides of the snowshoe frame.

Instead of extensible coil spring sections 38 other known means may be employed for making straps 34 and 36 adjustable in length.

As shown in Figure 7 the position of the heel of the boot is controlled by coaction between the heel piece 24 and strap means 42 and 44 which at their front ends respectively are attached to the snowshoe on either side of the boot, and preferably adjacent the toe cord, and have their other or rear ends attached to the heel piece 24 at points 46 and 48 which are spaced substantially from the rear of the heel of the boot. The rear ends of strap means

42 and 44 can be attached to instep strap 20 but as shown they are attached to the heel piece 24 adjacent the respective front ends of the heel piece and close to the points of interconnection between the heel piece 24 and instep strap 20. As shown vertical slits 46 and 48 are provided in the respective ends of heel piece 24 to receive the strap means 42 and 44 but it will be understood said strap means 42 and 44 can be attached to heel piece 24 in other ways, as for example by rivets, or the ends of the heel piece itself may be extended to provide straps to serve the purpose of strap means 42 and 44.

Straps 42 and 44 serve the same purpose as the heel strap means 26 shown in Figures 1-4 and the heel strap means 32, 34 and 36 shown in Figures 5 and 6 which is to fix the position of the heel of the boot on the snowshoe and prevent it from swinging back and forth laterally of the snowshoe.

There has thus been provided a structure in which the objects of the invention are obtained in a thoroughly practical manner. The binding has the advantages of simplicity and of economy and easy transferability as a unit from one snowshoe to another and the parts may be readily replaced individually.

What I claim is:

- 25 1. A snowshoe binding adapted to provide control from the heel of the user's boot comprising, means attached to the snowshoe for limiting movement of the user's boot forwardly of the snowshoe, means for preventing movement of the toe of the boot laterally of the snowshoe and means adjustable in length for engaging the heel of the boot and exerting pressure on the boot to keep it in abutting relation with said stop member, said last mentioned means having portions extending forwardly and outwardly from the heel and adapted for attachment to the snowshoe at points spaced laterally of the snowshoe thus providing a triangular support with the base of the triangle substantially equal to the width of the snowshoe in its mid-portion.
- 30 2. A snowshoe binding comprising a toe piece for positioning the toe of a user's boot on a snowshoe, a heel piece extending around the heel of the boot, an instep strap for extending under the boot and around the user's instep, the respective forward ends of said heel piece being connected to said instep strap on opposite sides of the boot and held in position by said instep strap, and heel positioning means secured to the portion of the heel piece which extends around the rear of the heel of the boot and secured to the snowshoe at points on opposite sides of the boot and spaced apart laterally of the snowshoe a distance substantially equal to the width of the snowshoe.
- 35 3. A snowshoe binding comprising means for positioning the toe and preventing it from moving laterally or forwardly of the snowshoe and other means extending around the rear of the heel of the boot from points on the snowshoe in approximate alignment with the toe cord and spaced away from the sides of the boot by attachment to the snowshoe frame.
- 40 4. A snowshoe binding for positioning a user's foot on a snowshoe comprising, a toe piece, and flexible means extending forwardly from the user's heel and having diverging portions extending outwardly from the user's foot and adapted for attachment to the snowshoe at points spaced laterally of the snowshoe thus providing heel control from a base line which is substantially equal in length to the width of the snowshoe at said base line.
- 45 5. A snowshoe binding comprising means for positioning the toe and preventing it from moving laterally or forwardly of the snowshoe and other means extending around the rear of the heel of the boot from points on the snowshoe in approximate alignment with the toe cord and spaced away from the sides of the boot by attachment to the snowshoe frame.
- 50 6. A snowshoe binding for positioning a user's foot on a snowshoe comprising, a toe piece, and flexible means extending forwardly from the user's heel and having diverging portions extending outwardly from the user's foot and adapted for attachment to the snowshoe at points spaced laterally of the snowshoe thus providing heel control from a base line which is substantially equal in length to the width of the snowshoe at said base line.
- 55 7. A snowshoe binding comprising means for positioning the toe and preventing it from moving laterally or forwardly of the snowshoe and other means extending around the rear of the heel of the boot from points on the snowshoe in approximate alignment with the toe cord and spaced away from the sides of the boot by attachment to the snowshoe frame.
- 60 8. A snowshoe binding for positioning a user's foot on a snowshoe comprising, a toe piece, and flexible means extending forwardly from the user's heel and having diverging portions extending outwardly from the user's foot and adapted for attachment to the snowshoe at points spaced laterally of the snowshoe thus providing heel control from a base line which is substantially equal in length to the width of the snowshoe at said base line.
- 65 9. A snowshoe binding for positioning a user's foot on a snowshoe comprising, a toe piece, and flexible means extending forwardly from the user's heel and having diverging portions extending outwardly from the user's foot and adapted for attachment to the snowshoe at points spaced laterally of the snowshoe thus providing heel control from a base line which is substantially equal in length to the width of the snowshoe at said base line.
